APPARATUS FOR THE MANUFACTURE OR
TREATMENT OF TEXTILE MATERIALS

Henry Dreyfus, London, England

Application June 3, 1936, Serial No. 83,272
In Great Britain June 12, 1935

7 Claims. (Cl. 117—2)

This invention relates to apparatus for the manufacture or treatment of filaments, threads, yarns and the like, and particularly crêpe and other threads containing filaments of cellulose acetate.

U. S. Patents Nos. 2,088,587 and 2,088,628 describe a new process for the production of crêpe threads of cellulose acetate filaments by which there may be obtained crêpe effects of excellence hitherto unattained by such materials. The process comprises subjecting the threads to the action of steam, under conditions such that moisture is present, during the application of the crêpe twist, as by applying steam, under the said conditions, to the travelling thread over at least a portion of that part of its track in which twisting actually takes place. The process enables cellulose acetate crêpe threads to be produced which have an average strength very much greater than that of cellulose acetate crêpe threads produced by a simple twisting operation without steaming during twisting, characteristic of the new process. Further, apart from the great advantage that the resulting thread or fabric made therefrom is strong, the twisting operation itself is greatly facilitated in that twisting may be accomplished satisfactorily under conditions of twist and spindle speed which, in the absence of the steaming step, would give rise to frequent thread breakage.

The subjection of the thread to the action of the steam may be carried out in operations in which the crêpe twist is applied in more than one stage, the steam being applied at least in the stage in which there is applied the final amount of twist necessary to impart the crêpe property to the thread.

I have found that apparatus which may be employed for steaming travelling filaments, threads, yarns and the like advantageously consists of a steam chamber, a hollow member, hereinafter referred to as the thread member, through which the thread to be steamed may be passed and having an inlet and outlet for the thread, and a member connecting the steam chamber to the thread member, and affording passage to steam from the steam chamber to the thread member. In general a plurality of thread members will be supplied with steam by a common steam chamber, the threads to be steamed being passed through the thread members while steam is being passed into these members.

Preferably the connecting member and/or the thread member have sufficient surface exposed to the atmosphere to ensure that the steam in the

thread members is in a wet condition. Part or all of the connecting member and/or the thread member advantageously have walls of a metal, such for example as copper or brass, which is of good conductivity. For example the connecting member may comprise a long tube of narrow bore or the connecting member and/or the thread member may be provided with cooling fins or ribs, or both these features may be employed.

I have found that the best results are obtained by providing a pressure drop between each thread member and the common steam chamber and by maintaining a sufficient pressure in the steam chamber or by employing a steam chamber of sufficiently large diameter to permit the passage of steam largely in excess of the requirements of the thread members connected to the steam chamber.

The pressure drop may be brought about by any convenient means. Thus, for example, tubes of the same dimensions and of small cross-section may be inserted in each connection, or a constriction may be made in each connection, the passage left through the constriction having the same dimensions in each connection. Advantageously, however, the pressure drop is capable of adjustment by the operator. One method of securing a pressure drop capable of adjustment is to insert in each connection a similar diaphragm constituted by a plate of standard thickness pierced by holes of various sizes. A change in the pressure drop is obtained by movement of the diaphragm by the operator so that the steam is passed through a larger or smaller hole in the diaphragm. A further method of obtaining a pressure drop which can be adjusted by the operator is to insert a needle valve in each connection. When a perforated diaphragm, valve or other form of constriction is used it should be spaced apart from the thread member and advantageously is adjacent to the steam chamber.

The steam chamber may be of any convenient dimensions sufficient to ensure an adequate supply of steam to each of the connections to the thread members, steam being admitted at one or both ends of the chamber and/or at one or more points along its length. In general pressures of $\frac{1}{2}$ or 1 up to 5, 10, 15 or even 30 lbs. per square inch or more may be maintained in the steam chamber during operation. Where the chamber is small, higher pressures may be employed than when the chamber is large. For instance, pressures of 5 to 30 lbs. per square inch may be employed with a steam chamber consisting of a pipe having an internal diameter of $\frac{1}{2}$ ".

The thread members are preferably of small circular cross-section (e. g. of from $\frac{1}{8}$ to $\frac{1}{2}$ inch internal diameter) and made of a metal, such for example as copper or brass, which is of good conductivity.

The length of passage of the thread through the steam depends upon the duration of the steaming treatment required. For example, where the thread passes at a speed of about 2 metres per minute, a three-inch passage through the steam has been found to give satisfactory results. Lengthier treatments may, however, be employed, as for example by passing the thread at the said speed through six to twelve inches of steam or more. The thread member provided for the passage of the thread is therefore of sufficient length to give the required period of treatment. To give the same period of treatment with high speeds the length of the passage is proportionately greater. Where the inlet or outlet openings are in the bottom of the thread member, the opening may have a wall or rim projecting into the member so as to prevent water collecting in the member escaping by this opening. A suitable drain may be provided to lead this water from the thread member.

Condensation of the steam in the connections and in the thread members ensures that moisture is present. This is an important feature of the new apparatus, which thus overcomes difficulties due to the tendency of the steam to become superheated by expansion from a higher to a lower pressure. At the same time the convenience of using a comparatively high supply pressure is retained. The steam chamber itself may, however, be lagged to minimize condensation otherwise than in the connecting and thread members.

One construction of the apparatus of the invention, when fitted on a twisting machine comprising a plurality of fairly closely spaced twisting spindles, comprises a steam-pipe of say $\frac{1}{2}$ " or $\frac{5}{8}$ " internal bore extending over the length occupied by a number of spindles and connected by copper pipes of small diameter e. g. $\frac{1}{8}$ ", each fitted with a needle valve, to a series of narrow vertical pipes open at each end, and set in such a position above each spindle that the threads from the spindles are conveniently passed through them. In order that solid particles should not be carried from the steam chamber a gauze or other suitable filter is provided at the junction of the steam pipe and each connecting pipe.

When in operation, each thread member is disposed on a twisting machine at a suitable point in the track of a thread from a twisting spindle to the winding device. For example, each member may be disposed so that the inlet opening for a thread is substantially in line with a vertical twisting spindle. If desired, the said inlet opening may actually form the guide usually disposed above the spindle to receive the thread drawn over the end of the package rotating with the spindle. Thus the twisting device may be of the kind in which a device is provided to restrict the ballooning of the thread, for example a flyer or other floating ring device as described in Patent No. 1,784,581. The thread may, therefore, proceed direct from the flyer or floating ring device or from the surface of the package direct to the inlet opening of the thread member, provided such opening is disposed substantially in line with the twisting spindle at a suitable distance from the spindle.

There may, however, be an additional guide dis-

posed between the thread member and the top of the spindle, in which case the thread may enter the thread member at a distance of, say $\frac{1}{2}$ to 3 inches, e. g. 1 to 2 inches, from the said fixed guide. Preferably the twisted thread proceeds directly from the outlet opening of the thread member to the traverse guide of the take-up device. Therefore, with the thread member disposed so that its inlet opening forms a fixed guide above the twisting spindle and its outlet opening arranged to conduct the thread direct to the traverse guide of the take-up device, the steaming operation may be carried out with relatively little deviation of the thread.

If desired a ring twisting device may be used in which case the thread passes through the thread member and is steamed on its way to the twisting spindle. The thread is thus twisted while under the influence of steam.

One construction according to the invention is illustrated in the accompanying drawing, in which

Fig. 1 is a front elevation of apparatus for steaming yarn while inserting twist therein;

Fig. 2 is a cross-section showing the steaming device in greater detail and taken along the axes of the connecting member and the thread member;

Fig. 3 is a modification of the apparatus shown in Fig. 1.

Referring to Fig. 2, the steaming device consists of a steam-pipe 1 of about $\frac{1}{2}$ inch bore, into which is screwed a plug 2 having a channel 3 for the passage of steam and a filter 4 of wire gauze to prevent passage of rust and other solid matter. Screwed into the plug 2 is a second plug 5, to which is soldered a copper connecting tube 6, having a length of $1\frac{1}{2}$ to 3 inches and an internal diameter of about $\frac{1}{8}$ inch fitted with cooling fins 7. Passage of steam from the steam-pipe 1 to the connecting tube 6 is controlled by means of the adjustable needle 8 mounted in the plug 5 and seating in the hole 12. A copper tube 9, having a length of about 3 inches and an internal diameter of $\frac{1}{16}$ inch is soldered onto the end of the connecting tube 6 at right-angles thereto and permits of passage of travelling thread through the steam supplied to it from the steam-pipe 1 by way of the needle valve 8 and the connecting pipe 6. Porcelain collars 10, 11 are provided at the two ends of the copper tube 9 to reduce chafing of the thread in entering and leaving the tube.

Fig. 1 illustrates an arrangement suitable for steaming yarn while inserting twist therein. Yarn 20 is twisted as it is drawn off, through a floating ring 21, from a bobbin 22 mounted on a vertical spindle 23, as is more fully described in Patent No. 1,784,581. The yarn leaving the twisting device is passed direct to the lower end of the vertically disposed copper thread member 9 of the steaming device illustrated in Fig. 2 and described above, the porcelain collar 11 thereof being arranged vertically above the spindle 23 and thus serving as a thread guide for the twisting device. The steamed and twisted thread emerges from the steaming device at 10 and is taken up by a suitable winding device (not illustrated) as described in Patent No. 1,784,581 above.

The steam-pipe 1 is provided with a plurality of steaming devices, as illustrated and described above, spaced along its length, the lower end of each thread member 9 being similarly vertically disposed over the spindle of a twisting device as described above.

Fig. 3 illustrates an arrangement similar to

that of Fig. 1, but modified by the provision of an additional thread guide 24 disposed between the top of the spindle 23 and the porcelain collar 11.

While the apparatus has been described principally with reference to the crêpe twisting of cellulose acetate threads described in the specifications referred to, it may be used in any process wherein filaments, threads or yarns are steamed. It is not only applicable to processes of steaming and twisting normally spun cellulose acetate threads, but can be used in processes of steaming other materials, e. g. stretched cellulose acetate yarns, regenerated cellulose yarns and yarns of natural silk, during the insertion of twist. Treatment of yarns of viscose silk in this way permits of the production of materials of increased tenacity and crêping power. The apparatus may also be employed in the stretching of travelling threads in the presence of wet steam, by the processes described in British Patent No. 438,584. Such a stretching may, for example, be carried out while inserting in the threads a comparatively low degree of twist, say under 10 turns per inch, for example 2 to 5 turns per inch.

Having described my invention what I desire to secure by Letters Patent is:—

1. Apparatus for steaming travelling textile filaments and threads, comprising a steam supply chamber, a hollow thread member for passage of the material to be steamed, a connecting member joining said steam chamber to said thread member, and means adapted to cool steam passing through said connecting member and to ensure in said thread member a supply of steam cooled to saturation.

2. Apparatus for steaming travelling textile filaments and threads, comprising a steam supply chamber, a hollow thread member for passage of the material to be steamed and, joining said steam chamber to said thread member, a connecting member comprising a tube having walls of material of good thermal conductivity and having sufficient surface exposed to the atmosphere to ensure in the thread member a supply of steam cooled to saturation.

3. Apparatus for steaming travelling textile filaments and threads, comprising a steam supply chamber, a hollow thread member for passage of

the material to be steamed, and a tube connecting said steam chamber to said thread member, said tube having a constriction at a point in its length spaced apart from the thread member.

4. Apparatus for steaming travelling textile filaments and threads, comprising a steam supply chamber, a plurality of hollow thread members for passage of the materials to be steamed, and a tube joining each thread member to the steam supply chamber, said tube having a constriction at a point in its length spaced apart from the thread member.

5. Apparatus for steaming travelling textile filaments and threads comprising a steam supply chamber, a hollow thread member for passage of the material to be steamed, and, joining said steam chamber to said thread member, a connecting member having, adjacent to the steam chamber, an adjustable constriction and comprising a long tube of small cross sectional area adapted to cool steam passing therethrough and to ensure in the thread member a supply of steam and moisture.

6. Apparatus for steaming a thread during the insertion of twist therein, comprising a hollow thread member for the passage of thread undergoing twisting, a steam supply chamber, a connecting member joining said steam chamber to said thread member, means adapted to cool steam passing through said connecting member and to ensure in said thread member a supply of steam cooled to saturation, and a twisting spindle arranged to insert twist in the thread while the latter is under the influence of the steam in the thread member.

7. Apparatus for steaming a thread during the insertion of twist therein, comprising a twisting spindle, a tubular thread member for the passage of thread undergoing twisting by rotation of said spindle and disposed substantially coaxially with the spindle so that twist is inserted while the thread is in the thread member, a steam supply chamber, a connecting member joining said steam chamber to said thread member, and means adapted to cool steam passing through said connecting member and to ensure in said thread member a supply of steam cooled to saturation.

HENRY DREYFUS.
